UNITED STATES PATENT OFFICE.

FRANCIS I. PALMER, OF CHICAGO, ILLINOIS.

DESIGN FOR A BADGE.

SPECIFICATION forming part of Design No. 22,744, dated August 29, 1893.

Application filed May 31, 1892. Serial No. 435,071. Term of patent 3½ years.

To all whom it may concern:

Be it known that I, FRANCIS INGREM PALMER, a citizen of the United States, residing at 68 Hartford Building, 140 Dearborn street, 5 in the city of Chicago, county of Cook, and State of Illinois, have invented and produced a new and original Design for a Campaign-Button, of which the following is a specification, reference being had to the accompanying drawings, forming part thereof.

Figure 1 is a face view of button or badge and Fig. 2 a side section thereof.

The badge comprises for its leading fea-

tures in the drawings referred to, A, the all seeing eye in the center; B, the name space 15 on top; C, the two flags of liberty the stars and stripes of the United States below.

Having fully described my invention, what I claim, and desire to secure by Letters Patent, is—

The design for a badge herein shown and described.

FRANCIS I. PALMER.
